UNITED STATES PATENT OFFICE.

JAMES J. DAVIS, OF COLUMBUS, OHIO.

MEANS FOR WARMING SHOW-WINDOWS.

No. 923,149.

Specification of Letters Patent.

Patented June 1, 1909.

Application filed June 5, 1908, Serial No. 436,818. Renewed March 1, 1909. Serial No. 480,756.

To all whom it may concern:

Be it known that I, JAMES J. DAVIS, a citizen of the United States, residing at Columbus, in the county of Franklin and State of Ohio, have invented certain new and useful Improvements in Means for Warming Show- Windows, of which the following is a specification.

My invention relates to the improvement 10 of means for warming show windows and the objects of my invention are to provide improved means for imparting to the inner surfaces of show windows, heat sufficient to prevent the formation thereon of frost or visible 15 moisture; to so construct my improved heating appliance as to provide an equal distribution of the heated air over the window surfaces; to prevent the mixture of burned gas and heated air and to produce other improvements, the details of which will be more fully 20 pointed out hereinafter.

These objects I accomplish in the manner illustrated in the accompanying drawing, in which:

25 Figure 1 is a transverse section of a store-room floor showing the inner surfaces of store windows with my improved window warming mechanism in place, Fig. 2 is a sectional view on line $x-x$ of Fig. 1, Fig. 3 is a 30 plan view of one of the heat distributing pipe retaining plates, and, Fig. 4 is a sectional view on line $z-z$ of Fig. 3.

Similar numerals refer to similar parts throughout the several views.

35 1 represents the floor of a store-room, 2 the show windows or glass window plates, which for the purpose of illustration I have shown on opposite sides of a door 3, and 4 represents the window display floors or platforms 40 which ordinarily project inwardly from the bases of the window frames which are indicated at 2^a .

In carrying out my invention, I support or 45 suitably suspend by means of hangers 5 which depend from the underside of the floor 1 within the basement of the building, an upright heater casing 6 which has the general form of a truncated cone and the lower end of which is open. Extending horizontally into the casing 6, is a gas supply 50 pipe 7 which carries centrally in said casing a perforated burner ring 8. Extending through this ring and supported therein, is the lower end of a central vertical air tube 9, the upper 55 end of which in the upper portion of the casing 1 supports the upper end of a second or

intermediate substantially cone-shaped casing 10, with an opening in the upper end of which the tube 9 communicates. Leading horizontally outward from the upper portion 60 of the casing 10 is an outlet pipe 11 provided with a suitable damper 12.

From the upper end of the conical casing 6 lead upwardly and outwardly the desired 65 number of heat conducting pipes 13, each of the latter being provided with a suitable damper 13^a . Each of the pipes 13 leads to the central portion of a horizontal head or pipe section 14 which is located beneath the floor 1 and beneath the display platform of a 70 window. From each of these pipes 14 lead upward through the floor 1 and thence through openings in the display platform 4, a plurality of comparatively small pipes 15. The openings in the window platform through 75 which the heat distributing pipes 15 lead, are arranged in a longitudinal row at intervals one from the other adjacent to the inner side of the lower window frame bar 2^a and that portion of each of the distributing pipes 15 80 which projects through the platform, fits within the central opening of a suitable metallic plate or disk 16 which is screwed or otherwise secured to the upper surface of the platform 4.

In operation, it will be understood that when the gas is lighted at the openings of the burner 8, the heat generated thereby will operate to heat the tube 8 and the outer and inner casings 6 and 10, with the result that the 90 air which will be drawn upward between said outer and inner casings will become heated and will pass outward through the pipes 13 to the pipe heads 14 and thence be distributed through the pipes 15 to the bases of the 95 windows. Owing to the fact that the outlets of the pipes 15 are arranged at equidistant points between the sides of the window base, it is obvious that the heat which rises from 100 said outlets, will be equally distributed against the inner face of the glass plate 2 and that any tendency of moisture to accumulate on the window glass through condensation occasioned by the warmer air of the interior of the store coming into contact with the 105 colder glass, will be obviated. In this manner it will be understood that show windows may be kept clear of obstruction and in a desirable transparent condition.

Owing to the provision in the heating apparatus of the internal casing 10 and the outlet 11, it will be understood that the 110

- burned gas or products of combustion which may arise from the burner, may pass outward without becoming mingled with the heated air which passes through the external casing and through the tube 9. Although I have shown a gas burner in connection with the heating device, it is obvious that other means of heat generation may be employed.
- What I claim, is:
- 10 1. In a show window warming means, the combination of a heat generator and casing supported beneath a store-room floor, heat pipes leading upward therefrom, and horizontal pipe sections connected with the discharge end of said heat pipes, of a plurality of smaller heat distributing pipes leading from said horizontal pipe sections to points on the inner side of and adjacent to the bases of display windows.
- 15 2. In a show window warming means, the combination with a heating appliance supported beneath the floor of a store-room comprising separated external and internal casings, said internal casing having an outlet 20 in its upper portion, and heat generating means in its lower portion, heat pipes leading upward from said outer casing, horizontal pipe sections connected with the upper ends of said heat pipes, and a plurality of smaller 25 heat distributing pipes connected with each of said horizontal pipe sections, said heat distributing pipes having their outlets adjacent to the inner sides of the bases of the store windows.
- 30 3. In a show window warming means, the combination with a heating appliance supported beneath the floor of a store room, of an enlarged horizontally disposed heat pipe, a heat conducting pipe leading from said 35 heating appliance to said heat pipe, said heat pipe being also located beneath the floor, and

a plurality of smaller pipes rising from said heat pipe and passing through the floor of a show window.

4. In a show window warming means, the combination with a heating appliance supported beneath the floor of a store room, of an enlarged horizontally disposed heat pipe, a heat conducting pipe leading from said heating appliance to said heat pipe, said heat pipe being also located beneath the floor, a plurality of smaller pipes rising from said heat pipe and passing through the floor of a show window, plates into which the upper ends of said pipes project, said pipes being located on top of the show window floor, and means for securing said plates to said floor.

5. In a device of the character described, the combination with a show window, of a heating appliance supported beneath the floor of a store room in which said show window is located, said heating pipes comprising separated external and internal frusto-conical casings closed at their upper ends and open at their lower ends, a tube passing from the inner of said casings, an outlet pipe leading from the upper portion of the inner of said casings, a burner located in the inner of said casings and supporting said tube, a heat conducting pipe leading from the upper portion of the outer casing, an enlarged heat pipe to which said heat conducting pipe is connected, a damper in said heat conducting pipe, and a plurality of smaller pipes extending from the enlarged heat pipe to and through the floor of the show window.

In testimony whereof I affix my signature in presence of two witnesses.

JAMES J. DAVIS.
